UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

ANTIFRICTION BEARING.

Application filed December 27, 1924. Serial No. 758,346.

This invention relates to improvements in anti-friction bearings.

An object of the invention is to provide anti-friction bearings more particularly 5 adapted for use as side bearings for railway cars, in which the parts are so arranged that the anti-friction element is automatically returned to normal centered position under the influence of gravity when free from load. 10 A further object of the invention is to provide a bearing of this character in which novel centering means are provided, whereby in addition to returning the anti-friction element to centered position, such means 15 serve to retain the element in the mounting, the arrangement being such as to permit shifting of the anti-friction element with reference to the centering means so as to present new wearing surfaces and insure uniform wear on such element. 20

A still further object of the invention is to provide a bearing of this character in combination with the centering means referred to, in which a plain steel roller may 25 be utilized, and the centering means applied thereto without mutilation of the roller, or the necessity of providing projections or other securing means thereon.

Other and further objects of the invention 30 will more fully and clearly appear from the description and claims hereinafter following.

In the drawings, Fig. 1 is a vertical, partly sectional view, taken through the ends of 35 the body and truck bolsters of a railway car showing my invention in connection therewith. Figure 2 is a top plan view of the invention showing the same detached from the bolster, and Figure 3 is a transverse, sectional view of the invention on the line 3—3 40 of Figure 1.

Referring to the drawings, A indicates the under side of a body bolster and B the upper side of the corresponding spaced truck bolster of the railway car. My improved side bearing is shown as applied to the truck bolster and comprises broadly a mounting 45 in the form of a suitable housing C, an anti-friction element D, centering and retaining means E and counter-weights F adapted to 50 co-operate with the guide means G provided in the mounting.

The housing C is preferably provided with 55 curved end walls 5, inturned stop flanges 6 at the upper edges of the end walls 5, and

end flanges 7 to provide means for securing the housing in position. The side walls 8 of the housing C are provided with offset portions 9 providing the guide means F, which guide means are disposed on opposite sides 60 of the housing C and are in the form of arcuate recesses or pockets 10 open at their bottoms and their inner sides. The housing C is entirely open at the bottom and the end walls 5 of such housing are recessed at their 65 lower ends, for a suitable distance to fit over a bearing plate 11, the flanges 7 of the housing being secured to the bearing plate by means of rivets 12, and the bearing plate in turn being secured to the bolster plate B by 70 means of rivets 13, the bearing plate 11 forming the bottom of the housing.

The anti-friction element D is preferably 75 in the form of a cut-off section of a cylindrical rolled steel bar, of a length to fit crosswise within the housing so as to leave a suitable space between the inner sides of the side walls 8 of the housing and the ends of the element D, for the application of the centering means hereinafter referred to. 80 The anti-friction element is arranged to roll upon the bearing plate 11 in the usual manner from end to end of the housing C.

The centering and retaining or connecting means E are preferably in the form of a 85 rectangular yoke 14 adapted to fit over the reduced top portion of the element D, and being of a width less than the major circumference of said anti-friction element, so that the yoke member 14 rides upon and is supported by the periphery of the roller, the engaging portions of the yoke preferably 90 being curved as indicated at 15 to secure an accurate fit. The yoke 14 is provided with depending extensions 16 at each side 95 of the element D, and formed on the lower ends of each of the depending extensions 16 is the counter-weight F, such counter-weights projecting laterally into the guide means G as clearly shown in the drawings. 100

Each counter-weight F is of a width which will permit the same to oscillate in the guide means G, and the upper portions thereof are arcuate in shape to conform to the configuration of the guide means, being normally 105 spaced from the upper wall of the guide means when the anti-friction element is in centered position, each of such counter-weights being arranged to exert a pull upon the anti-friction element D and the yoke 14 110

when the same is moved to either side of normal centered position.

In operation of the device, assuming that the anti-friction element D is moving toward the right as shown in dotted lines in Figure 1, the yoke is tilted by reason of its engagement with the element D, displacing vertically to some slight extent the counterweights F, and disposing the same at one side of the center of gravity of the element D and the yoke 14, so that when load is removed from said element, the same will be returned to centered position by the counterweights F through the medium of the yoke 14 acting upon such element. During continuous operation of the device in the manner above set forth there will be certain automatic shifting movement of the element D with reference to the yoke 14, resulting in the constant presentation of new wearing surfaces of the element D so as to ensure uniform wear thereupon and minimize any tendency to produce flat spots.

An important feature of applicant's invention resides in providing the yoke which permits the use of counter-balancing centering means in connection with a plain, un-mutilated roller, such counter-balancing means being of a character to retain the roller in the housing and permit automatic shifting of the roller relative to the yoke, to present new wearing surfaces during the normal operating of the device.

While I have herein shown and described what I now consider the preferred manner of carrying out my invention, the same is merely illustrative and I contemplate all changes and modifications that come within the scope of the claims appended hereto.

40 What I claim is:

1. In an anti-friction bearing, the combination with a mounting adapted to be applied to the bolster of a vehicle; of an anti-friction element movably engaging said mounting; an independent retaining device including means disposed in supporting contact with the peripheral bearing surface of said element in regions above the horizontal central plane of said elements; counterweights connected to said means; and means for causing displacement of said element to either side of centered position, said means serving to movably confine said counterweights and maintain said retaining device in assembled relation with said mounting.

2. In an anti-friction bearing, the com-

bination with a mounting adapted to be applied to the bolster of a vehicle; of an anti-friction element movably engaging said mounting; a yoke disposed in supporting contact with the peripheral bearing surface of said anti-friction element above the axial center thereof and being of a size less than the size of said anti-friction element at said axial center, said yoke being provided with depending projections; counter-weights on said projections; and guide means in said mounting movably retaining said counter-weights.

3. In an anti-friction bearing, the combination with a housing adapted to be secured to a bolster or the like, and having a solid bearing surface associated therewith; of an anti-friction element proper disposed partially within said housing, said element having a bearing surface adapted to cooperate with said first named bearing surface and an oppositely disposed bearing surface disposed exteriorly of the housing, said element being adapted to move to either side of normal central position when actuated under load; and combined, gravity actuated self-centering, retaining means, disposed in supporting contact with the outer peripheral bearing surface of said anti-friction element and embracing the same to retain said element in assembled relation with the housing, said element being adjustable with respect to said means whereby to present different bearing surface portions, said means being held in assembled relation with said housing.

4. In an anti-friction bearing, the combination with a mounting adapted to be applied to a bolster or the like and having a bearing surface associated therewith; of a plain cylindrical roller adapted to move back and forth on said bearing surface; guide means associated with said mounting and being vertically arranged; an independent retaining device having counterweighted portions mounted in said guides and movably retained thereby, said device being disposed in supporting contact with the opposite sides of the curved surface of the roller above the center thereof to maintain the said roller in assembled relation with said mounting; said retaining device operating to center said roller when free from load.

In witness that I claim the foregoing I have hereunto subscribed my name this 5th day of December, 1924.

JOHN F. O'CONNOR.
